Term of patent 14 years

(Cl. D16—2)

FIG. 1

Des. 185,957

PAGE 2

FIG. 2

FIG. 3

FIG. 4

FIG. 5

Figure 1 is a right side elevational view of a portable hand fire extinguisher showing our new design;

Figure 2 is a top plan view thereof;

Figure 3 is a front elevational view thereof;

Figure 4 is a detail in side elevation and partly in section taken on line 4—4 of Figure 3; and

Figure 5 is a bottom perspective view thereof.

The dominant features of our design reside in the full line portions of the drawing, the broken line portion of the tank being broken away in Fig. 3 and being omitted from Fig. 5 for convenience of illustration.

We claim:

The ornamental design for a portable hand fire extinguisher, as shown and described.
